Des. 183,668
Patented Oct. 7, 1958

183,668

NURSING NIPPLE

William A. Whalen, Manchester, Conn.

Application May 17, 1957, Serial No. 46,208

Term of patent 3½ years

(Cl. D83—8)

FIG.1

FIG.2

FIG.3

I claim:

The ornamental design for a nursing nipple, as shown.
